[57] CLAIM

The ornamental design for a housing for a silicon controlled rectifier device, as shown.

DESCRIPTION

FIG. 1 is a perspective view of a housing for a silicon controlled rectifier device embodying the new design;

FIG. 2 is a side elevation of the housing in FIG. 1 as seen from the left hand side thereof;

FIG. 3 is a front elevation of the housing shown in FIG.

1;

FIG. 4 is a top plan view of the housing as shown in

FIG. 1;

FIG. 5 is a side elevation of the housing as shown in

FIG. 1 as seen from the right hand side thereof; and

FIG. 6 is a rear elevation of the housing as shown in

FIG. 1.
